UNITED STATES PATENT OFFICE.

GROVER D. BUSSARD, OF LITTLETON, COLORADO.

VALVE-SPRING COMPRESSOR.

Application filed January 3, 1925. Serial No. 333.

To all whom it may concern:

Be it known that I, GROVER D. BUSSARD, citizen of the United States of America, residing at Littleton, county of Arapahoe, and 5 State of Colorado, have invented certain new and useful Improvements in Valve-Spring Compressors; and I do declare the following to be a full, clear, and exact description of the invention, such as will enable 10 others skilled in the art to which it appertains to make and use the same, reference being had to the accompanying drawings, and to the characters of reference marked thereon, which form a part of this specification. 15

This invention relates to improvements in valve spring compressors.

Internal combustion engines of the type employed in connection with automobiles 20 are, with a few exceptions, provided with intake and exhaust valves of the poppet type. Poppet valves are held against their seats by means of helical springs, one end of which abuts a disk held in place on the 25 stem by means of a removable pin. Before a valve can be removed it is necessary to remove the pin and this can only be done after the spring has been compressed enough to permit the disk to be moved sufficiently to allow the pin to be removed. 30 The springs that hold the valves in place are usually quite powerful and resort must therefore be had to a special tool for the purpose of compressing the same.

I am aware that several specifically different kinds of valve spring compressors have been invented and that some of these are used with more or less success.

It is the object of this invention to produce a valve compressor that shall be of 40 simple, cheap and substantial construction and which can be employed with equal facility in connection with ordinary poppet valve engines and with valve in head engines.

It is a further object of this invention to produce a device that can be easily assembled and disassembled so that it can readily be packed for shipment or carried in a tool box.

My invention can be most clearly explained and will be most readily understood when reference is had to the accompanying drawing in which the preferred form thereof has been shown and in which

Fig. 1 shows my device in position for compressing the valve spring.

Fig. 2 is a section taken on line 2—2 Fig. 1.

Fig. 3 is a section taken on line 3—3 Fig. 1 and shows the pawl member in the proper 60 position to make the ratchet device operative.

Fig. 4 is a section similar to Fig. 3 but showing the pawl in inoperative position, 65 and

Fig. 5 shows my invention, with parts reversed, applied to a valve in head construction.

In Fig. 1 I have shown a portion of an engine block 1 which is provided with a 70 port opening 2 that is closed by means of a valve 3. This valve has a stem 4 that projects downwardly and is adapted to be engaged by the valve tappet 5. A disk shaped member 6 is applied to the valve stem 4 75 near the end thereof, and held in place thereon by means of a pin 7. A coil spring 8 encircles the stem, one end of this spring abuts the horizontal wall portion 9 of the engine block, while the other end rests on 80 the disk 6. Spring 8 is normally of greater length than the distance from 9 to 6 and is therefore under compression wherefore it exerts a force which tends to move the valve 3 against its seat. When the valve is to be 85 ground, or removed for any other purpose, the pin 7 must first be removed. This cannot be done unless the spring 8 is first compressed to such an extent that the pin 7 can be grasped by the fingers or by a tool. 90 As the springs 7 are usually quite stiff and require a considerable force to compress them and as they are often located in such a position that they are not readily accessible it becomes necessary to provide a special 95 tool for compressing them.

My improved valve spring compressor consists of a flat bar 10, one edge of which is provided with gear teeth 11 which adapt the bar to function as a rack. The side of 100 the bar adjacent to the other edge is provided with a series of ratchet teeth 12. Secured to the lower end of the bar 10 is a bracket 13 (Figs. 1 and 2). This bracket is provided at its outer end with two spaced 105 members 14 that are adapted to receive between them the stem 4 and to engage the disk 6. The other end of bracket 13 has two spaced parallel members 15 adapted to receive the bar 10 to which the bracket 110 is secured by means of a pin 16. It will be noted that the members 15 are provided

with holes 17 whose function will herein-after appear. Bracket 13 has a plate 18 projecting downwardly therefrom (Fig. 1). This plate is adapted to engage the edge of 5 the bar 10 so as to provide a stop means to resist rotation about the pin 16. A secured bracket which has been designated by numeral 19 is constructed exactly the same as the bracket 13 except for this that the end, instead of being forked, is curved downwardly 10 in the manner indicated by numeral 20. The point of the part 20 is adapted to engage the valve 3. The parts of bracket 19 that correspond to 15 and 18 of bracket 13 have been designated as 15^A and 18^A. A handle 21 has one end formed arcuate, 15 as indicated by numeral 22. This arcuate portion is provided with teeth 23 and is rotatable through an arc of substantially 20 180 degrees. It will be noticed that the teeth 23 do not project over the line of the upper edge of the handle and therefore when the handle is turned upwardly as far as it can 25 go the teeth 23 will not engage with the teeth 11, with the result that the bracket can be moved freely in any direction, so that it can be adjusted to the proper position. When the handle 21 is moved downwardly or rotated clockwise about its pivot 24 the teeth 23 and 11 will engage and form a rack 30 and pinion mechanism by means of which a strong force can be exerted tending to move the brackets towards each other. When the parts are in the position shown by full 35 lines in Fig. 1 and the handle 21 rotated to dotted line position (Fig. 1) the bar 10 and bracket 13 will be moved to dotted line position which, obviously, compresses the spring 8. Unless some ratchet means is 40 provided to prevent it, the spring 8 will move the brackets apart as soon as the handle is released. I have therefore pro- 45 vided each bracket with a detent 25. This detent has been shown in section in Figs. 3 and 4 and consists of a tubular member 26 provided with an axial opening through 50 which the pin 27 extends. A member 28 is secured to the pin 27 and serves as an abut- 55 ment for the spring 29, which is under com- 60 pression, and therefore exerts a force tend- 65 ing to move the pin into engagement with the ratchet teeth 12. To the outer end of pin 27, I secure a head 30. A pin 31 is 70 secured to the head 30 and is adapted to enter an opening in the end of member 26 75 in the manner shown in Fig. 3 in which position the pin 27 is operative as a pawl. If the pawl and ratchet is not desired, the 80 pin 27 is withdrawn sufficiently to remove 85 the pin 31 from the hole and the head 30 rotated slightly whereby the pin 31 will engage the end of member 26 and hold pin 27 in inoperative position. 90

When a valve in head motor is to be operated upon, the brackets 13 and 19 are preferably reversed in the manner shown in Fig. 5. The bracket 19 is fastened to the bar 10 by a pin 32 and the handle 21 transferred to the bracket 13. In Fig. 5 I have shown the spring compressed. 95

It is evident that the device may readily be separated into its four parts and that these can then be packed into a comparatively small space. 100

I desire to call attention at this point to the means that I have provided for adjusting the spread of the spaced members 14 so that they may be moved apart to the extent required to receive the largest size valve stem. The part marked 14^A is a separate member that is secured to member 13 by a rivet 35 which fits loosely in a hole in the part 14^A and permits the latter to move. A pin 36 secured to member 13 serves as a guide and the screw 37 which has a rotatable connection with member 13 and a threaded connection with member 14^A serves to move the latter with respect to the former and to spread the ends 14 to the extent required. 105

Although I have shown my device as employed in connection with valves and valve springs, this is only one use to which it can be put as it may be used wherever a clamp of this type is needed. 110

Having now described my invention what I claim as new is: 115

A valve spring compressor comprising a rack having gear teeth along one side, a bracket secured to one end of said rack and projecting laterally therefrom a second bracket slidably connected with the said rack, said brackets lying substantially in the same plane, a segmental pinion rotatably connected to the slideable bracket, said pinion being adapted to cooperate with the teeth on the rack in all but one position, means for turning said pinion, a pawl and ratchet device between the slideable bracket and the rack for holding the slideable bracket in adjustable position and a stop plate projecting outwardly from each bracket, said plates being adapted to engage the side of the rack. 120

In testimony whereof I affix my signature. 125

GROVER D. BUSSARD.
